UNITED STATES PATENT OFFICE.

GEORGE E. NYE, OF PROVIDENCE, RHODE ISLAND.

DESIGN FOR A SPOON.

SPECIFICATION forming part of Design No. 24,197, dated April 16, 1895.

Application filed March 19, 1895. Serial No. 542,418. Term of patent 14 years.

To all whom it may concern:

Be it known that I, GEORGE E. NYE, of the city of Providence, in the county of Providence and State of Rhode Island, have invented and produced a certain new and original Design for Spoons, of which the following is a specification, reference being had to the accompanying drawings, forming part thereof.

Figure 1 represents an obverse view of a spoon illustrating my new design. Fig. 2 represents a longitudinal sectional view of the same, taken on a line *a-b* Fig. 1.

The leading feature of my new design for a spoon resides particularly in the bowl portion of the spoon, and consists in the rounded end of the bowl the contour lines of the under and upper surfaces of which converge toward the delivery portion of the bowl into a spout or funnel around the outer end of which is a rib.

In the drawings 5 represents the handle of a spoon of which 6 is the bowl. The upper portion 7 and the lower portion 8 of the bowl are brought together in the rounded surface 9 from which the spout 10 extends, the contour lines of the upper and lower portions converging into the lines of the spout, and the rib or collar 11 embracing the outer end of this spout.

What I claim is—

The design for a spoon as herein shown and described

In witness whereof I have hereunto set my hand.

GEORGE E. NYE.
